WALL FORM

MacGregor S. Anderson, Chicago, Ill.

Application February 11, 1933, Serial No. 656,316

10 Claims. (Cl. 25—131)

The main objects of this invention are to provide an improved panel form for use in the construction of concrete walls; to provide a panel form having a facing of inexpensive material 5 adapted to be readily removed and reversed or replaced when desired, to provide panel forms of this kind which are constructed so as to permit any desired number of them to be coupled together edge to edge for building a mold of any 10 required dimensions; to provide an improved form of rim adapted to protect the edges of the facing material and also to serve as a seal for the abutting edges of the panels when coupled; to provide an improved form of tie which serves 15 not only as a tie and spreader to hold opposed panels in proper spaced relation, but also serves as a lock for temporarily coupling adjacent panels edge to edge in exact alinement; and to provide panel forms of this kind which can be readily 20 set up and dismantled by one unskilled laborer.

An illustrative embodiment of this invention is shown in the accompanying drawings, wherein:

Figure 1 is a side elevation showing one way of coupling five of the improved panels edge to 25 edge.

Fig. 2 is a fragmentary perspective of an improved wall form showing the method of applying horizontal and vertical liners to the backs of the panels.

Fig. 3 is an enlarged detail partly in section and partly in elevation, showing one method of attaching a liner to the panel frames.

Fig. 4 is a fragmentary perspective of a wall form showing the improved form ties which lock 35 the panels in assembled relation.

Fig. 5 is an enlarged perspective of one of the improved ties.

Fig. 6 is an enlarged detail showing the improved method of applying the tie to a panel.

Fig. 7 is a detail in section showing the abutting edges of two adjacent panels before they are clamped together, and Fig. 8 shows the same parts after being clamped together by the ties.

The improved panels to which this invention 45 is applied are preferably all identical in construction, size, and shape so as to obviate the necessity of sorting and to facilitate handling and storage of the panels.

The panels are rectangular and the width of 50 each is preferably two thirds of its length so that the panels may be joined together, either in the manner shown in Fig. 1, or as shown in Fig. 2, for constructing molds of different heights.

In the form shown, each panel comprises an 55 angle iron frame 1 having flanges 2 disposed

in a single plane to provide a support for a facing 3 which is detachably secured to the flanges 2 by bolts 4 or removable rivets, so as to permit the facings to be renewed when necessary. These facings may be made of metal, wood, or any 60 other suitable material.

Disposed at right angles to the flanges 2, are flanges 5 which form the bearing edges of the panels. Formed in these edges 5, are apertures 6 which are positioned so that, when the panels 65 are placed edge to edge, either as shown in Fig. 1 or as shown in Fig. 2, the apertures in the edges of one panel will register with those in the abutting edges of adjacent panels.

Nails 7 or other wedges may be inserted into 70 some of the registering apertures for interlocking the panels.

The flanges 5 are depressed adjacent certain of the apertures to form recesses 8 for receiving tie bands 9 which, as hereinafter described, hold 75 the form sides in proper spaced relation and also serve to interlock the abutting panels of each form side.

The panels may be braced by angle bars 10 which extend across the frame in engagement 80 with the rear of the facing.

In order to protect the edges of the facing against injury and also to seal the abutting edges of the panels against the leakage of concrete, each panel has a rim which circumscribes the 85 facing. This rim includes a portion 11 which is clamped between the facing and the frame by the bolts or rivets 4 and a border flange 12. The rim is preferably made of sheet metal having some resilience so that the flanges 12 will normally 90 diverge from the facing edges, as shown in Figs. 6 and 7, when the panels are not interlocked. When the panels are interlocked, the rim flanges 12 are pressed firmly against the facing edges, as shown in Fig. 8. The rim flanges 12 are 95 recessed, as shown at 13, so as to permit the tie bands to extend between the abutting edges of the panels.

The tie bands 9 are preferably formed of band iron having portions thereof struck out to provide opposite projecting dowels 14 adjacent each end thereof. These dowels are adapted to extend through certain of the apertures in the panel flanges 5 and they are provided with openings or sockets 15 for receiving nails 16 or other 105 wedges which engage the inner faces of the flanges 5. It will thus be apparent that the tie bands serve to hold the form sides in proper spaced relation to each other and also serve to firmly interlock the panels of each form side. 110

If desired, the form sides may be further braced by horizontal and vertical liners 17 and 18, respectively which are secured to the panel frames by yokes 19 which are provided with hooked ends 5 20 engaging certain of the apertures 6 of the frames. Blocks 21 are inserted between the base of each yoke and the outer face of the liner. The blocks 21 may be secured to the yokes 19 by nails 22, as shown in Fig. 2, or they may be provided with grooves 23 for receiving the base of the yoke, as shown in Fig. 3.

To erect a form of this improved construction, care should be taken to commence with a level base. The panels may be positioned vertically or 15 horizontally or some may be positioned vertically and others horizontally depending upon the height of the wall to be constructed. The tie bands are cut and formed at the factory so that it is necessary to select those of proper length 20 for the particular wall to be built.

In attaching the tie bands, the dowel parts 14 are inserted through certain of the registering apertures 6 of the abutting edges 5 of the panels and the nails 16 are then driven into the sockets 25 15 for forcing the abutting edges into firm contact, as shown in Fig. 8. In this position, the rims 12 will seal the joints against the leakage of concrete.

After the lower course of panels has been erected, another course may be built on top of it, either in the manner shown in Fig. 1, or as 30 shown in Fig. 2.

To insure proper alignment of the panels, the liners may be attached to one side of the form 35 in the manner indicated.

A mold of this construction is very easily dismantled. The liners are removed and then one panel at a time may be removed by merely knocking out the nails 16 which hold it in place. When 40 all of the panels have been removed, the extremities of the tie bands 9 will project beyond the concrete wall and these may be cut off flush with the concrete if desired.

Although but one specific embodiment of this 45 invention has been herein shown and described, it will be understood that details of the construction shown may be altered without departing from the spirit of the invention as defined by the following claims:—

50 I claim:

1. A wall form comprising a rectangular metal frame, a non-metallic facing mounted on said frame, and a yieldable metal rim mounted on said frame and surrounding the edges of said facing.

55 2. A wall form comprising a rectangular frame, a non-metallic facing mounted on said frame, and a yieldable metal rim surrounding the edges of said facing, said rim having a portion thereof clamped between said frame and facing.

60 3. A wall form comprising a plurality of rectangular panels adapted to be disposed edge to edge, resilient rims on the edges of said panels, and means for clamping said panels together and compressing said resilient rims.

65

4. A wall form comprising a plurality of rectangular panels adapted to be disposed edge to edge, each of said panels comprising a frame having a non-metallic facing, a resilient rim surrounding the edges of said facing, and fastening means for clamping said panels together with said rims abutting one another.

80

5. A form comprising a pair of panels having edges provided with apertures, said edges being recessed adjacent said apertures, said panels being adapted to be disposed edge to edge with the recesses of one registering with those of the other, fastening means in said recesses, each of said fastening means having oppositely projecting dowels extending through said apertures and provided with sockets therein, and keys adapted to be seated in said sockets for clamping said panels edge to edge.

85

6. A form comprising a pair of panels disposed in spaced relation to each other, the edges of said panels having apertures therein, tie members spanning the space between said panels and having dowel portions projecting through said apertures, and keys mounted on said dowels for securing said tie members to said panels.

90

7. A form comprising a pair of panels adapted to be disposed in substantially parallel spaced relation to each other, the edges of said panels having apertures therein, tie members spanning the space between said panels and having dowel portions projecting through said apertures, said dowel portions having sockets therein, and keys seated in said sockets for clamping said tie members to said panels.

100

8. In a form, the combination with a panel having apertures therein, of a tie comprising a strip of metal having portions thereof struck out from the normal plane thereof to form a pair of oppositely projecting dowels having key seats therein, said dowels being adapted to engage the apertures 115 in said panel, and keys seated in said seats for engaging portions of said panel.

110

9. A form comprising two side units arranged in spaced relation to each other, each of said units comprising a plurality of rectangular panels disposed edge to edge, the abutting edges of said panels having aligned apertures and recesses adjacent said apertures, tie members spanning the space between said side units and projecting into certain of the recesses in both units, dowels 125 formed on said tie members and projecting through certain of said apertures, said dowels having sockets therein, and keys seated in said sockets for clamping said tie members to said panels.

120

10. In a concrete form construction, a tie support having an aperture therein, a tie having a dowel portion bent out laterally from the normal plane of the tie for insertion in said aperture, said dowel having a key seat, and a key seated in said key seat and adapted to be wedged between opposed portions of said dowel and support.
